RADIOACTIVITY PROCESSING DEVICE

Orear Kenton Neville, Elmhurst, and Benjamin F. Scott, Chicago, Ill., assignors to Nuclear-Chicago Corporation, a corporation of Delaware

Application February 8, 1957, Serial No. 638,980

14 Claims. (Cl. 250—44)

This invention relates to radioactivity processing devices, and more specifically to devices employing radioactivity to ionize air for the elimination of static electricity.

One well-known type of device for the dissipation of electrostatic charge, in installations such as industrial plants and hospital operating rooms where there exists substantial hazard of explosion or other difficulties due to electrostatic charge, is to employ a radioactive source whose emanations are directed against the body whose charge is to be dissipated. Numerous objections to this type of device, however, exist. Such static elimination devices are in general suitable only for the dissipation of charge over relatively small areas. Further, the rate of charge removal is seriously limited by the fact that the intensity of the radiation employed cannot be made very high without constituting a hazard to personnel, unless elaborate precautions are taken to prevent interposition of parts of the human body in the beam of radiation.

With these things in view, it has been proposed to remove the static charges by means of radioactivity indirectly, i.e., to blow a stream of air over a source of radioactive emanations and thus to ionize the air, and then direct the ionized air against the charged body. See, for example, the paper of Quinton given at Oxford in 1954 and published at page 188, volume 2, "Radioisotope Conference, 1954," edited by J. E. Johnston (Academic Press Inc.). Devices of this nature, however, have not come into widespread use because of the large remaining hazards to personnel. Although the ionized air itself has no substantial harmful effect should portions of the human anatomy be interposed between the generator of the ionized air and the surface upon which the ionized air is directed, there nevertheless remains the substantial possibility of persons deliberately or accidentally placing portions of their bodies, such as their hands, in the direct beam of the radiation from the radioactive source, which is normally very intense in such applications. This hazard is particularly acute because of the nature of the installations in which such devices are designed to be used. In the vast majority of cases, the personnel in the industrial establishments, hospitals, etc., in which such static eliminators are required have no knowledge whatever of radioactivity or of its dangers. The mere placing of warning signs, warning labels, and similar safety paraphernalia has not been found to be adequate to permit the use of such devices in ordinary locations by untrained personnel with any degree of safety. The problem is even more acute because of the fact that the hazard from the radioactivity is unconnected with the operation or non-operation of the device. In the case of most other types of hazardous devices, such as, for example, devices employing sources of high voltage, the hazard exists only while the device is in operation. In preventing injuries to personnel by such devices, it is merely necessary to train those persons who may have contact with the device while it is in operation. In the

2

case of a device employing high intensity radioactivity, on the other hand, the hazard exists at all times, not only when the device is in operation, but when it is being shipped, when it is in a storeroom, or when it is in a junk-yard. It is thus obvious that the mere training of personnel in the measures necessary to insure their personal safety is inadequate to prevent the occurrence of accidents in the nature of radiation exposure.

It is the principal object of the present invention to provide a static eliminator device which is so safe that it is practical for use in virtually any type of installation, without the necessity of special training of personnel. Furthermore, the safety features of the present device are so designed that the device is not only safe when used in the manner for which it is designed, but in addition will cause no damage even under such extreme circumstances as might be encountered, if, for example, it should be lost or stolen and tampered with by a person completely ignorant of its dangers, such as a child. In providing such a structure for a static eliminator, it is found that the safety features of the present device may well be incorporated in other radioactivity processing devices. Since the hazards incident to radioactivity as discussed above have constituted a severe limitation on the general usage of radioactive materials in many other applications, the adaptation of the teachings of the present invention to a large variety of radioactivity processing devices will readily be made.

The most serious aspect of a radiation hazard is the cumulation of the damage done by the radiations. Momentary exposure to even a fairly strong source, particularly in the case of ionizing radiations, such as alpha or beta particle emitters, will do little if any body damage. However, where a device incorporating a radioactive source is to be permitted to appear in locations where it will be accessible to people completely ignorant of the nature of the device or its dangerous potentialities, there exists the risk of prolonged exposure. As an example, when an industrial establishment is determining whether to employ a device incorporating a radioactive source in its plant, it must consider the possibility of tampering with the device by a completely unauthorized person, who may, for example, remove the source from the device and place it in a location wherein, unnoticed, it constantly irradiates himself or one or more innocent persons who have no way whatever of knowing of the existence of the source. This possibility has constituted a very serious deterrent to the use of equipment employing such sources in any type of location in which it is not practical to take elaborate precautions to prevent such occurrences. Similarly, in shipping and other handling of devices incorporating such sources, it has been necessary to provide a variety of precautions against such tampering, all of which add so tremendously to the cost of purchasing and using such equipment that devices employing radioactivity have in general been shunned if any reasonable alternate has been available.

In some radioactivity processing devices, it is possible to place the source in a housing which serves as a shield and insert and remove materials to be irradiated through openings constructed and arranged to prevent the escape of radiations. In order to minimize the hazard of having ignorant persons tampering with the device and exposing the source, the shielding container may be securely locked, or even permanently sealed as by welding. However, reliance on a lock, no matter how well designed, is uncertain at best. Permanent sealing is not satisfactory, since such permanent sealing makes it impossible to ever replace the source, clean the interior or otherwise service the device. Furthermore, in the case of the completely sealed container, or of the locked container which is so secure that the locked cover, door, or other access por-

tion is completely secure against removal under all reasonable circumstances, the temptation is created to persons illicitly in possession of the device to saw through the shielding container (in ignorance of its function) and to thus gain access to the interior, creating the hazardous condition described above.

The essence of the present invention lies in the provision of a structure wherein the source is contained in a shielded container with access openings designed to prevent the escape of radiation as described above, but upon unauthorized tampering with the device in such a manner as to expose the source to the exterior, the source, which is in its normal condition the source of radiations which would be dangerous, is harmlessly dissipated and rendered inert and inactive.

In the present device, the source is incorporated in the device in the form of a normally sealed container filled with a radioactive gas and having a wall permeable to the radioactive emanations from the gas, the surrounding shield forming an irradiation chamber adjacent to the source, and there are provided means responsive to breaching of the shield to open the container to diffuse the gas into the surrounding atmosphere. In the most advantageous embodiments of the invention, the radioactive gas employed is krypton 85, which is known (see the paper of Arrol et al., at page 59 of the volume above cited) to have the highly desirable characteristics of being an intense source of beta rays of long half-life, but being essentially harmless when released into the atmosphere, since it is rapidly diffused and is immediately expelled by the human body if inhaled.

For a more complete understanding of the teachings of the invention, reference is made to the embodiment illustrated in the appended drawing, in which:

Figure 1 is a top plan view of a radioactivity static 35 eliminator embodying the teachings of the invention;

Figure 2 is a transverse sectional view taken along the line 2—2 of Figure 1;

Figure 3 is a longitudinal sectional view taken along the line 3—3 of Figures 1 and 2; and

Figure 4 is a fragmentary view corresponding to a portion of Figure 3, but illustrating the manner in which a portion of the apparatus may be disabled.

It will be seen that the shield or housing of the apparatus, of a suitable material such as aluminum, consists generally of a flat base plate 10 integral with a top portion 12 of arcuate cross-section and an end portion 14; at the other end is an end cover generally designated 16. The upper portion of the end cover 16 is provided with a tongue 18 of arcuate cross-section and a peripheral shoulder 20 forming a stop for the end of the top shield portion 12 into which the tongue 18 is thus closely nested. A shorter tongue 22 on the bottom portion of the end cover 16 overlaps the end of the bottom plate 10, which abuts against a shoulder 24 on the cover. The cover is held in place by bolts 26, the heads of which are covered by a heavy metal strap 28. The strap 28 is seated in a groove 30 in the top shield 12, the groove 30 and the strap 28 extending around the entire girth of the device except the base plate 10. One end of the strap 28 is hinged at 32 to one side of the base plate, and the opposite end of the strap 28 is locked to an ear 34, attached to the base plate, by a hasp 36 and a key-operated lock 38. The strap 28 is sufficiently resilient so that removal of the lock 38 permits swinging away of the strap 28 from the cover to expose the heads of bolts 26. When the latter are removed, the cover may readily be removed from the balance of the shield.

To each side of the upper surface of the base plate 10 are secured blocks 40 having diagonally cut sides 42 forming with the top surface of the base plate 10 an undercut keyway retaining a radioactive source container 44. The source container 44 is generally rectangular in internal shape and is formed from a block of suitable material such as stainless steel, with a radiation-perme-

able top closure. The outer surfaces of sides 46 are formed with a suitable diagonal pitch to slide in the keyway formed by the blocks 40. One end of the container 44 abuts against the end portion 14 of the enclosure, and the opposite end of the container has an ear 48 secured by a screw 50 to the base plate 10, thus locking the source container securely in place. The source container 44 may readily be removed upon removal of the screw 50, after removal of the cover 16.

10 The upper wall of the source container 44 is a thin sheet of mica 52 which is permeable to the radiations of the krypton 85 contained within the source container. The edges of the radiation-permeable wall or window 52 are sealed to the body of the container 44 by fused glass 54. A plug 56 of fused glass seals the filling aperture of the source container.

15 The end cover shield 16 is formed with an air inlet chamber 58 between the outer end of the cover and a baffle plate 60 which has an air passage slot 61 in the lower lower region thereof and is secured by screws 62 to an internal shoulder 64 on the cover. The end of the cover is apertured in the upper region thereof at 66, and an air flow fitting 68 is secured to the outer surface of the end cover and connected to the outlet of an air blower 70. The latter, being of conventional design, is shown in the drawing merely in block form for purposes of simplicity. The opposite end of the housing is provided with an outlet dispersal nozzle 72 formed with an offset to prevent the exit of radiation. Both the inlet and outlet air passages are of a size and shape to block insertion of human fingers into the interior of the housing.

20 Suspended from the inner surface of the top cover or shield 12 by brackets 74 is a transversely extending pivot pin 76. Secured in central position on the pivot pin by bearing collars 78 is a knife having a pointed and sharpened lower end at 82.

25 Wound about the pin 76 are helical springs 84 and 86 having their outer ends secured to the brackets 74 and their inner ends hooked on the edge of the knife 80 and urging the knife in the direction in which the point 82 would penetrate the thin mica wall or window 52. However, the knife 80 has a cam or stop portion 88 abutting against the tongue 18 of the end cover shield 16, thus maintaining the knife 80 in a withdrawn position against the urging of the springs 84 and 86.

30 On the end of an extension 90 on the knife 80 is a ferromagnetic slug 92 which is closely adjacent to a portion of the top of the housing which has an internally threaded well 94 filled by an externally threaded plug 96 provided with a socket 98 which permits removal of the plug by means of a suitable wrench.

35 As shown in Figure 4, there is employed as an auxiliary to the device a strong rod magnet 100 having the end thereof threaded in the same manner as the plug 96, so that the plug can be replaced by the magnet. When the magnet 100 is screwed into the well 94, the force of the magnet on the ferromagnetic slug 92 draws the slug to the inner surface of the top shield portion 12, and thus latches the knife 80 against motion as long as the magnet 100 is in position.

40 The construction of the illustrated device having been described, the purpose and mode of operation of the various features will be readily understood. As indicated by arrows in the drawing, ambient air is drawn in by the blower 70 and blown into the aperture 66 and the air inlet chamber 58. It enters the main body of the shielded chamber through the slot 61 and proceeds over the irradiation region adjacent to the window or radiation-permeable wall 52, the air thus ionized 45 leaving the device through the nozzle 72 to be dispersed over a surface on or adjacent to which the device is placed. Both the offsetting of the inlet aperture 66 and the slot 61 and the offset shape of the outlet nozzle 72 prevent escape from the chamber not only of primary

radiations from the source, but additionally of secondary radiations directly generated by the primary radiations. The ionized air emitted by the nozzle 72 is harmless, and produces no radiation effects.

It will thus be seen that the illustrated device is well suited to accomplish the purpose of eliminating static electricity over substantial areas. The strength or intensity of the radioactivity source may be selected in accordance with the size of the device and the ionization capacity which it is designed to have. In most applications a few millicuries of krypton 85 may be successfully employed, but sources of much higher intensity may be used if desired. Purity of the gas is not critical, but where the gas is obtained as a fission product, it is of course necessary to remove contaminants which would impair the safety of the present device. Krypton 85 also produces a slight amount of gamma radiation, but this creates no substantial hazard, being orders of magnitude smaller than the beta radiation.

It is to be noted that the locking device comprising the strap 28 which overlies the bolts 26, and its associated hinge and lock, is not designed to provide the maximum possible assurance against tampering with the device. On the contrary, perhaps the most important purpose of the locking device is to provide an obvious access point for unauthorized persons, who might otherwise create a serious radiation hazard. The shield is constructed of a far thicker gauge material than is actually required for absorption of the beta radiations from the source. The rather insecure locking device, when combined with the thickness of the shield, serves to assure that ignorant persons attempting to gain access to the interior will do so by separation of the two portions of the enclosure. When access is gained in this manner, as the operation of removing the cover is commenced, the removal of the end of the tongue 18 releases the knife 80, which thereupon, under the urging of the springs 84 and 86, ruptures the window or wall 52, and thus permits diffusion of the gas within the source container into the atmosphere. The krypton 85 is rendered completely harmless by such dispersion, even if kept within a sealed room of moderate size.

The auxiliary disabling means for the knife 80 consisting of the ferromagnetic slug 92 and the magnet 100 is for use by authorized personnel for the purpose of gaining access to the interior for operations such as cleaning, if such should be necessary, or replacement of the source. In addition, of course, the magnet 100 is employed to disable the knife when the device is being assembled. Where the device is to be used in a type of installation where it is not desired that any of the personnel have access to the interior of the device, neither the magnet 100 nor instructions for opening are supplied to the user, the maintenance operations, if any are required, being performed solely by the manufacturer or a suitable service agency, to whom the device is returned for any such service that may be required. It is, of course, technically possible to disable the knife by insertion of any magnet sufficiently strong into the well 94, and thereupon to disassemble the shield without rupturing the window of the source. However, the likelihood of this being done by any person who has not been instructed in the manner of opening the device or the nature of its internal construction is so small as to be completely negligible.

It will thus be seen that the illustrated static eliminator is highly suitable for use in a location in which no special precautions are taken concerning radiation hazards. It will be further seen that the essence of the features of the construction of the device may be adapted to many types of devices for radioactivity processing of materials other than air. Further, many variants of the construction shown will readily be devised. Certain of the features can, if not necessary for particular applications, be

omitted, and likewise in some applications it will be desirable to add additional features. Thus if access to the interior without opening the normally sealed source container is not required, no provision need be made for such access. Likewise the source container may be so shaped and disposed that breaching of the shield in any fashion whatever necessarily opens the source container. In another modification, the flat source container illustrated is mounted centrally, rather than at one side, of the irradiation region, and is provided with radiation-permeable windows on both sides. In a still further modification, the chamber through which the air flows is enclosed in a surrounding chamber containing a non-radioactive compressed gas, and release of the gas from the source container is accomplished in response to a fall in pressure of the non-radioactive gas.

Obviously, the teachings of the invention will be adapted by persons skilled in the art to many embodiments far different in both appearance and details of construction from the illustrated generator of ionized air. Accordingly, the scope of the invention should not be deemed to be limited by the particular embodiment thereof shown in the drawing, but shall be determined only by the appended claims.

What is claimed is:

1. A static electricity eliminator comprising at least two wall portions forming a closed chamber having an air inlet passage and an air outlet passage each constructed and arranged to block passage of both primary and secondary beta particles from the chamber, an air blower operatively connected to one of said passages, a normally sealed container of krypton 85 having a wall permeable to beta particles within the chamber, mechanism normally responsive to the motion of one of the wall portions with respect to the other of the wall portions to open the container to diffuse the krypton 85, and means operable from the exterior of the chamber to disable the mechanism and thus to enable opening of the chamber while retaining the krypton 85 in the container.
2. An ionized air generator comprising a closed chamber having an air inlet and an air outlet, means for forcing air through the chamber, a container within the chamber having therein a quantity of krypton 85 and having a wall permeable to beta particles, means for opening the chamber to provide human access to the interior thereof, means normally responsive to opening of the chamber to open the container and thereby permit escape of the krypton 85 into the air, and means independent of the opening of the chamber to disable the container-opening means.
3. A radioactivity processing device comprising a chamber adapted to receive a substance to be irradiated with beta particles, an access opening to the chamber, a closure member, means for securing the closure member over the access opening, a normally sealed container of krypton 85 having a wall permeable to beta rays within the chamber, and means responsive to removal of the closure member to open the container to permit the escape of the krypton 85.
4. A radioactivity processing device comprising a normally sealed container filled with a radioactive gas and having a wall permeable to the radioactive emanations from said gas, a shield substantially surrounding said wall and forming a chamber adjacent to said wall impermeable to emanations from the container but adapted to receive substances to be exposed to radiation, and mechanism responsive to opening of the shield to open the container to diffuse the gas into the surrounding atmosphere.
5. A device as described in claim 4 having means operable from the exterior to disable the container-opening mechanism.
6. A radioactivity processing device comprising a normally sealed container filled with a radioactive gas and having a wall permeable to the radioactive emanation

from the gas, a shield impermeable to such emanations surrounding said wall and forming an irradiation chamber adjacent to said wall, an access passage through said shield of a shape and size to pass a substance to be irradiated but to block passage through the shield of any portion of the human anatomy, and means responsive to breaching of the shield to open the container to diffuse the gas into the surrounding atmosphere.

7. A static electricity eliminator comprising at least two wall portions forming a closed chamber having an air inlet passage and an air outlet passage each constructed and arranged to block passage of both primary and secondary ionizing particles from the chamber, an air blower operatively connected to one of said passages, a normally sealed container of a gas emitting ionizing particles having a wall permeable to such particles within the chamber, mechanism normally responsive to the motion of one of the wall portions with respect to the other of the wall portions to open the container to diffuse the gas, and means operable from the exterior of the chamber to disable the mechanism and thus to enable opening of the chamber while retaining the gas in the container.

8. A static electricity eliminator comprising at least two wall portions forming a closed chamber having an air inlet passage and an air outlet passage each constructed and arranged to block passage of both primary and secondary ionizing particles from the chamber, an air blower operatively connected to one of said passages, a normally sealed container of a gas emitting ionizing particles having a wall permeable to such particles within the chamber, and mechanism responsive to the motion of one of the wall portions with respect to the other of the wall portions to open the container to diffuse the gas.

9. The device of claim 3 having externally operable means to disable the container-opening means.

10. A safety-shielded radioactive source assembly comprising a normally sealed container filled with a radioactive gas, a shield enclosure substantially surrounding the container, means coupled to the container and responsive to opening of the shield enclosure to open the container to diffuse the gas into the surrounding atmosphere, and

externally operable means independent of the opening of the shield to disable the container-opening means.

11. A safety-shielded radioactive source assembly comprising a normally sealed container filled with krypton 85, a shield enclosure substantially surrounding the container, means coupled to the container and responsive to opening of the shield enclosure to open the container to diffuse the krypton 85 into the surrounding atmosphere, and externally operable means independent of the opening of the shield to disable the container-opening means.

12. A radioactivity source adapted to be dissipated upon occurrence of an unsafe condition comprising a container filled with krypton 85, at least a portion of the container being permeable to beta rays, means adjacent to the container for opening the container to release the krypton 85, and mechanism responsive to occurrence of the unsafe condition to actuate the opening means.

13. A radioactivity source adapted to be dissipated upon occurrence of an unsafe condition comprising a container filled with a radioactive gas, at least a portion of the container being permeable to emanations from the gas, means adjacent to the container for opening the container to release the gas, and mechanism responsive to occurrence of the unsafe condition to actuate the opening means.

14. A safety-shielded radioactivity device comprising a normally closed chamber having at least one opening adapted to pass a substance to be exposed to radioactivity, a normally sealed container of radioactive gas permeable to the radiation from said gas within the chamber, the chamber being of a material shielding the exterior from radiations, and means responsive to opening of the chamber to open the container to disperse the radioactive gas.
